UNITED STATES PATENT OFFICE

ARTHUR L. BLACK, OF COFFEYVILLE, KANSAS

SEPARABLE OR DETACHABLE BOLT EYE

Application filed January 5, 1929. Serial No. 330,648.

This invention relates to a separable or detachable bolt eye for use in connection with suspension, lifting and anchorage purposes and has for its object to provide, in a manner as hereinafter set forth an article of such class, constructed and arranged for expeditiously positioning the same in cooperative relation with respect to the head of a bolt and further formed in a manner to arrest turning movement of the bolt relative thereto when the latter is mounted therein and extended therefrom.

Further objects of the invention are to provide, in a manner as hereinafter set forth a separable or detachable bolt eye which is simple in its construction and arrangement, strong, durable, compact, thoroughly efficient in its use, readily connected to and removed from a bolt, capable of being employed with bolts of varying lengths and diameters, and inexpensive to manufacture.

With the foregoing and other objects in view the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a side elevation of a bolt eye in accordance with this invention showing the adaptation thereof with respect to a bolt.

Figure 2 is a sectional elevation of the bolt eye and further illustrating the adaptation thereof with respect to a bolt.

Figure 3 is a top plan view of the bolt eye.

Figure 4 is a section on line 4-4 Figure 2.

Figure 5 is a section on line 5-5 Figure 1.

Figure 6 is a section on line 6-6 Figure 2.

In the drawings 1 denotes the head and 2 the threaded shank of a bolt. The shank 2 is for extension through the object 3, such as a metallic sheet which is to be suspended, transported, lifted or anchored, by a desired means, 50 not shown, for such purpose which is to be

attached to the bolt eye, in accordance with this invention. Mounted on the shank 2 is a nut 4 which supports the object 3 as well as clamps the latter against the bolt eye.

A bolt eye, in accordance with this invention comprises a base 5, preferably of oval contour. The base 5 has the top thereof dished transversely and upon an arc. The top of the base 5 is indicated at 6. Formed in the top 6, centrally thereof is a polygonal shaped sprocket 7. The base 5 is provided with a transversely extending slot 8 opening at its top at the bottom 9 of pocket 7 and at its bottom at the lower face of the base 5. The slot 8 is disposed transversely of the base 5, is of rectangular contour, and further is elongated in a plane transverse to the plane of the eye. The length of the slot 8 is slightly less than the greatest width of the pocket 7, but the walls of the slot 8 at the ends of the latter intersect the walls of the pocket 7. See Figures 3 and 4.

Formed integral with each end of the top 6 of base 5, is an upstanding arch-shaped coupling member or element 10 having its inner face 11 forming a continuation of the arc of the top 6 of base 5. The element 10 comprises a top 12 and a pair of arms 13, 14. The arms 13 merge into the ends of the top 6 of base 5. The lower portions of the arms 13, 14 are indicated at 15 and are flared. The top 12 of element 10 is of circular cross section.

Element 10 is employed for attaching to the bolt eye means employed for transporting, suspending, anchoring or lifting the bolt eye. The polygonal shaped pocket 7 is adapted to receive the head 1 of the bolt and owing to the shape of such pocket it prevents the bolt turning relative to the bolt eye. The slot 8 owing to the length thereof provides for the expeditious inserting of the shank 2 of the bolt in the bolt eye when the latter is to be arranged in co-relation with respect to the bolt. When the nut 4 is mounted on the shank 2 of the bolt the latter is detachably connected to the bolt eye.

When the bolt is to be mounted in and suspended from the bolt eye, it is positioned at an inclination as indicated by dotted lines 100

in Figure 5 and 16. The length of the slot 8 permits of this manner of inserting the bolt as the latter can quickly be inserted in the bolt eye and after the shank has been extended through the slot 8 the bolt can be shifted to a vertical position and the head thereof will seat in the pocket 7. The shank of the bolt can then be passed through the object to be suspended, transported or lifted and after which the nut 4 will be mounted in position.

It is thought that the many advantages of a separable or detachable bolt eye, in accordance with this invention can be readily understood, and although the preferred embodiment of the invention is as illustrated and described, yet it is to be understood that changes in the details of construction can be had which will fall within the scope of the invention as claimed.

20 What I claim is:

1. A separable or detachable bolt eye comprising a base and an arch-shaped coupling member integral therewith, said base having a polygonal shaped pocket in its top for the reception of the head of the bolt and further having a rectangular slot for the passage of the shank of the bolt, said slot opening at the bottom of said pocket and further having its walls intersecting the walls of the pocket and elongated in a plane transverse to the plane of said arch shaped member.

2. A separable or detachable bolt eye comprising a base and a coupling member integral therewith; said base having a polygonal shaped bolt head receiving pocket in its top and a slot opening into the pocket for the passage of the bolt shank and elongated in a plane transverse to the plane of said coupling member.

40 In testimony whereof, I affix my signature hereto.

ARTHUR L. BLACK.
